UNITED STATES PATENT OFFICE.

ALONZO HUNTLEY, OF HADLEY, ILLINOIS.

SPRING-GUN.

SPECIFICATION forming part of Letters Patent No. 674,771, dated May 21, 1901.

Application filed May 10, 1900. Serial No. 16,142. (No model.)

To all whom it may concern:

Be it known that I, ALONZO HUNTLEY, a citizen of the United States, residing at Hadley, in the county of Pike and State of Illinois, 5 have invented certain new and useful Improvements in Spring-Guns; and I do declare the following to be a full, clear, and exact description of the invention, such as will enable others skilled in the art to which it applies to make and use the same.

The invention relates to spring-guns.

The object of the invention is to provide a gun of this character which shall be simple of construction, durable in use, comparatively 15 inexpensive of production, and thoroughly efficient in operation.

With this object in view the invention consists in a spring-plunger for expelling a projectile, means for retracting the same and 20 for holding it retracted, and an adjustable stop for limiting the forward throw of the re- tracting means.

In the accompanying drawings, Figure 1 is a side elevation of a part of a gun-stock illustrating my invention, the hammer being thrown back and the spring-actuated plunger being compressed, as shown in dotted lines. Fig. 2 is a top plan view. Fig. 3 is a vertical longitudinal sectional view, and Fig. 4 is a 30 side elevation of the complete gun.

In the drawings, 1 denotes a portion of the barrel of a gun, one side of the lock-ease plate being removed, and 2 denotes the bore. Arranged within this barrel is a spring-actuated plunger 3.

4 denotes the hammer, pivoted in a recess in the stock and connected to the rear end of the spring-actuated plunger by a straight cord or thong 7.

40 8 denotes a pivoted trigger which is provided with a notch 9 to engage the toe of the hammer and which will hold the hammer cocked.

10 denotes a spring secured to the side of 45 the lock-ease and having one end bent, as at 11, and projecting into a longitudinal recess 12 in the side of the lock-ease and bearing against the upper end of the trigger to force it rearwardly. This spring is provided with an 50 aperture 13 at its bend, through which extends a stop-screw 14, arranged in the path of move- ment of the hammer. This screw acts as a stop for the hammer, thus regulating the

throw of the spring-actuated plunger, and consequently the distance of the throw of the 55 projectile. By working the screw inwardly the spring-plunger is given a greater range of movement, and consequently the projectile will be hurled a greater distance than it would be when the screw is worked out rear- 60 wardly.

From the foregoing description, taken in connection with the accompanying drawings, the construction, operation, and advantages of the invention will be readily understood 65 without requiring an extended explanation.

The device is exceedingly useful for the purpose for which it is designed and may be placed upon the market at a comparatively 70 small cost.

Various changes in the form, proportion, and the minor details of construction may be resorted to without departing from the principle or sacrificing any of the advantages of 75 this invention.

Having thus fully described my invention, what I claim as new, and desire to secure by Letters Patent, is—

1. In a spring-gun, the combination with a stock and its barrel, of a spring-actuated 80 plunger located within the barrel, a hammer, a flexible connection between the spring-actuated plunger and the hammer, a trigger adapted to engage a toe projecting from the hammer and hold it cocked, a spring-plate 85 secured to the stock and projecting within the path of the trigger to force it rearwardly, and an adjustable stop arranged within the path of movement of the hammer to regulate the throw of the spring-actuated plunger, 90 substantially as set forth.

2. In a spring-gun, the combination with a stock and its barrel, of a spring-plunger for expelling a projectile, means for retracting the same and for holding it retracted, and an 95 adjustable stop for limiting the forward throw of the retracting means, substantially as set forth.

In testimony whereof I have hereunto set my hand in presence of two subscribing wit- 100 nesses.

ALONZO HUNTLEY.
